(57) **CLAIM**

The ornamental design for a television set, as shown and described.

DESCRIPTION

FIG. 1 is a front, right perspective view of a television set showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view;

FIG. 9 is an enlarged detail view of portion 9 from FIG. 1; and,

FIG. 10 is an enlarged detail view of portion 10 from FIG. 8.

Broken lines illustrate portions of the television set that form no part of the claimed design.
